(57) **CLAIM**

The ornamental design for an element of article of clothing, as shown and described.

DESCRIPTION

FIG. 1 is a top plan view of an element of article of clothing showing my new design;

FIG. 2 is a bottom plan view thereof; and,

FIG. 3 is a sectional view taken along the lines 3—3 in FIG. 1.

The broken lines showing a part of a pair of trousers are for illustrative purposes only and do not form part of the claimed design.
